UNITED STATES PATENT OFFICE

147,329

DESIGN FOR A CASE FOR A RELIGIOUS SHRINE OR THE LIKE

William Taylor Jones, Scranton, Pa., assignor to
Consolidated Molded Products Corporation,
Scranton, Pa., a corporation of Delaware

Application March 19, 1946, Serial No. 127,668

Term of patent 14 years

(Cl. D29—23)

To all whom it may concern:

Be it known that I, William Taylor Jones, a citizen of the United States, residing at 440 S. Main Ave., Scranton, in the county of Lackawanna and State of Pennsylvania, have invented a certain new, original, and ornamental Design for a Case for a Religious Shrine or the like, of which the following is a specification, reference being had to the accompanying drawing, forming part thereof.

Figure 1 is an elevational view in open position of a case for a shrine embodying my new design and illustrating the inside of the case.

Figure 2 is an elevational view showing the outside of the case in an open position.

Figure 3 is a horizontal cross-sectional view through the center of Figure 1.

I claim:

The ornamental design for a case for a religious shrine or the like, as shown.

WILLIAM TAYLOR JONES.
